US00D886298S

(12) **United States Design Patent** (10) Patent No.: **US D886,298 S**
(45) Date of Patent: ** Jun. 2, 2020

(54) **TROCAR**

(71) Applicant: **KYOCERA CORPORATION**,
Kyoto-shi, Kyoto (JP)

(72) Inventors: **Takaharu Fujii**, Kyoto (JP); **Takashi Saotome**, Kyoto (JP); **Hiroki Taoka**, Kyoto (JP)

(73) Assignee: **Kyocera Corporation**, Kyoto (JP)

(**) Term: **15 Years**

(21) Appl. No.: **29/662,216**

(22) Filed: **Sep. 4, 2018**

D774,192 S * 12/2016 Fuchs D24/146
D779,671 S * 2/2017 Fuchs D24/147
D782,076 S * 3/2017 Teufel D25/146
D785,175 S * 4/2017 Zhou D24/146
D790,700 S * 6/2017 Zhou D24/146
D794,791 S * 8/2017 Zhou D24/146
D797,288 S * 9/2017 Zhou et al. ....
D797,289 S * 9/2017 Zhou D24/146
D800,307 S * 10/2017 DeNeui D24/146
D813,389 S * 3/2018 Zhou D24/146

(Continued)

Primary Examiner — George D. Kirschbaum

(74) Attorney, Agent, or Firm — Volpe and Koenig, P.C.

(57) **CLAIM**

The ornamental design for trocar, as shown and described.

DESCRIPTION

Related U.S. Application Data

(63) Continuation-in-part of application No. 35/502,437, filed on Aug. 15, 2016 (U.S. filing date under 35 U.S.C. 384), and having an international filing date of Aug. 15, 2016, now abandoned.

(30) **Foreign Application Priority Data**

Feb. 17, 2016 (JP) 2016-003371

(51) **LOC (12) Cl.** **24-02**

(52) **U.S. Cl.**

USPC **D24/146**

(58) **Field of Classification Search**

USPC D24/146, 147
